UNITED STATES PATENT OFFICE.

GEORGE EMERY MEGRAW, OF OAKLAND, CALIFORNIA.

DESIGN FOR A WATCH-CHAIN.

45,121.

Specification for Design.

Patented Jan. 6, 1914.

Application filed October 23, 1913. Serial No. 796,971. Term of patent 3½ years.

To all whom it may concern:

Be it known that I, GEORGE EMERY MEGRAW, a citizen of the United States, residing at Oakland, in the county of Alameda and State of California, have invented a new, original, and ornamental Design for Watch-Chains, of which the following is a specification, reference being had to the accompanying drawing, which forms a part thereof.

I claim—

The ornamental design for a watch chain as shown.

In testimony whereof I affix my signature in presence of two witnesses.

GEORGE EMERY MEGRAW.

Witnesses:

R. M. OYARZO,
F. P. SCHROEDER.
